UNITED STATES PATENT OFFICE.

SEWELL A. KNAPP, OF SAN FRANCISCO, CALIFORNIA, ASSIGNOR TO FREDERICK A. BRAND, OF SAN FRANCISCO, CALIFORNIA.

KNOCKDOWN BARREL.

1,165,335.

Specification of Letters Patent. Patented Dec. 21, 1915.

Application filed March 19, 1914. Serial No. 825,765.

To all whom it may concern:

Be it known that I, SEWELL A. KNAPP, a citizen of the United States, residing in the city and county of San Francisco and State of California, have invented new and useful Improvements in Knockdown Barrels, of which the following is a specification.

This invention relates to knock-down barrels.

10 The objects of the invention are to provide a simple, substantial, cheaply manufactured barrel, of sheet metal or other suitable material, which can be quickly assembled or knocked down and reset up; to provide 15 means for holding the sides of such a barrel securely together in the assembled position; and to provide means for securing a practically moisture-proof connection between the overlapping edges of the barrel.

20 A further important object is to provide a metal barrel with a wooden head, and to so design and arrange the parts that the portions of the metal barrel expanded to form the crozes for the heads will act as rollers or 25 tires on which the barrel may be rolled, the wooden head forming an inward support like the hub and spokes of a wheel against the indentation or collapse of the barrel.

20 A further object is to construct the chime so that it forms a proper seat and backing 25 for the head and also to reinforce the chime against collapse or indentation.

Further objects will appear hereinafter.

30 The invention consists of the parts and 35 the construction and combination of parts as hereinafter more fully described and claimed, having reference to the accompanying drawings, in which—

40 Figure 1 is a side elevation, partly broken away, showing the metal barrel assembled. Fig. 2 is a cross section of same, showing the joint in the side of the barrel.

45 Referring to the drawings, the barrel consists of a sheet A of metal or other suitable material having such inherent rigidity as to maintain the sheet in the form of a cylinder, or allow it to be partially opened when the barrel is knocked down. This sheet is first rolled to form crozes 2 and 3 for the 50 reception of the heads 4 and 5 respectively; also to form grooves 6 for a plurality of circumferential tie wires 7. One edge of the sheet is then folded back upon itself, as at 8, and then returned, as at 9, to form a pocket 10 extending along one lengthwise edge to

receive the opposite edge 11 when bent into cylindrical form. A metal sheet thus rolled and bent is then ready for assembling. This is accomplished as follows: The free end 11 of the rolled sheet is first inserted into the 60 pocket 10, head 4 being inserted at the same time. The tie wires are then applied and fastened, preferably in the manner indicated at 12. The barrel thus assembled is 65 very rigid and substantial in construction and is well adapted as a package for carrying heavy materials, such as nails, cement, and the like. A strip of cloth or other fibrous material 14, saturated with paraffin or other material insoluble in water and running the full length of the barrel, is inserted 70 between the free end 11 of the barrel and the pocket. This makes a positively tight joint and also guards against the admission of moisture when materials, such as cement, 75 or the like, are being transported. The barrel once assembled with the head 4 in position is first filled and tamped with the material to be shipped and the head 5 is then inserted. For the purpose of further reinforcing and strengthening the barrel it may 80 in some instances be desirable to roll a wire or strip of metal 13 in the chime of the barrel. Upon arriving at a destination the top 85 can be easily taken out and the contents removed. The tie wires fastened in the peculiar manner shown at 12 can be easily removed by a special form of tool, thus permitting the sheet to become released and allowing the barrel to fall apart. The sheets 90 of several barrels, together with the heads, can then be nested and shipped back to the factory or packing house, as the nesting of same consumes very little space.

95 Preferably the heads 4 and 5 are made of wood and the crozes 2-3 are formed by spinning or expanding the body of the sheet to form continuous circumferential convexities with corresponding interior concavities to receive the heads 4 and 5 and at the same 100 time form annular protuberances or rollers, as it were, on which the barrel may be rolled; the heads 4 and 5 forming inward supports for these rollers.

105 In order to form and strengthen the chimes of the barrel, the ends of the sheet constituting the barrel are bent over to form an inwardly and downwardly projecting annular flange 15 which is bent over so as to approach the surface of the head; this flange 110

15, with the body of the cylindrical sheet, forming a cylindrical pocket to receive the metal ring or band 13 which is securely clamped in the pocket and is adapted to bear 5 on the end of the head 4 or 5 and reinforce the croze.

The materials and finish of the several parts of the barrel are such as the experience and judgment of the manufacturer may 10 dictate.

Having thus described my invention, what I claim and desire to secure by Letters Patent is—

A barrel comprising a body of flexible 15 material rolled into cylindrical form and having circumferential convexities adjacent each end thereof forming corresponding concavities within the body constituting crozes, heads engaged in the crozes, there

being annular grooves immediately below 20 the convexities, the ends of said body having inwardly directed continuous annular flanges, the free edges of which bear against the heads adjacent the crozes, and tie wires engaged in said grooves, said tie wires being 25 under pressure so as to slightly compress the body on the inner faces of the heads to positively hold the heads in the crozes and in binding engagement with the free edges of said flanges.

In testimony whereof I have hereunto set my hand in the presence of two subscribing witnesses.

SEWELL A. KNAPP.
